Inventor
By *R. L. Lampert, Jr.* Atty.

UNITED STATES PATENT OFFICE.

HENRY H. LAMPERT, OF CHICAGO, ILLINOIS.

BAR SUPPORT AND SPACER.

1,361,162.

Specification of Letters Patent.

Patented Dec. 7, 1920.

Application filed October 15, 1919. Serial No. 330,791.

To all whom it may concern:

Be it known that I, HENRY H. LAMPERT, a citizen of the United States of America, and a resident of Chicago, county of Cook, and 5 State of Illinois, have invented certain new and useful Improvements in Bar Supports and Spacers, of which the following is a specification.

The main objects of this invention are to 10 provide an improved construction and arrangement of bar supporting means for use in supporting and clamping in place bars used in reinforced concrete construction; to provide an improved construction and arrangement 15 of the bar clamping and spacing means; to provide an improved construction of separately formed supporting members for said clamping and spacing means; to provide an improved manner of assembling 20 said supporting members on said spacing means; and to provide improved means for securing said supporting members on said spacing and clamping means.

An illustrative embodiment of this invention 25 is shown in the accompanying drawings, in which—

Figure 1 is a perspective view of an improved bar support and spacing device constructed in accordance with this invention, 30 one of the clamping means being shown in normal position prior to a bar being clamped in place, and the other clamping means being shown bent around a bar for the purpose of securing it in place.

Fig. 2 is a perspective view of one of the 35 supporting members.

Fig. 3 is a perspective view of a section of the spacing strip showing the arrangement of notches and recesses prior to the 40 supporting members being assembled on the strip.

Fig. 4 is a cross-sectional view taken on the line 4—4 of Fig. 1, showing how the supporting members are secured in place on 45 the strip.

Fig. 5 is a perspective view of a construction of this kind showing a slightly modified manner of securing the supporting members to the spacing-strip.

Fig. 6 is a sectional elevation of the same. 50 The embodiments of this invention as illustrated in the drawings, comprise a spacing member or strip 1 upon which the clamping means in the form of arms 2 are 55 integrally arranged, and supporting members 3.

The spacing member 1 is in the form of a comparatively narrow strip of wrought metal, preferably straight from end to end and of uniform cross-section. At intervals 60 along the length thereof pairs of notches 4 extend inwardly from one edge thereof about half the width of the strip, and between these pairs of notches recesses 5 extend inwardly from the opposite edge of the strip. 65

The arms 2 are struck out from opposite edges of the strip 1 and on opposite sides of the pairs of notches 4 and recesses 5.

The supporting members 3 are herein shown in the form of inverted U-shaped 70 chairs comprising depending legs 6 connected at their upper ends by a transversely disposed part 7. Notches 8 extend inwardly from the edges of the legs 6 directly below the transverse part 7. The depth of these 75 notches is about half the width of the member. A lug 9 is struck out from the transversely disposed part 7 which, as will more fully hereinafter appear, coacts with the recess 5 for securing the members 3 in their 80 assembled positions on the spacing strip 1.

The spacing strip 1 and supporting members 3 as thus formed are assembled by passing the notches 8 in the legs 6 of the supporting members 3 over the strip 1 to embrace that portion of the strip beyond the notches 4, while at the same time the notches 4 receive and embrace the legs 6 beyond the notches 8 as is clearly shown in Figs. 1 and 5. Thus assembled, the lug 9 is bent down 90 into the recess 5 and around the edge 10 of the strip 1. Thereupon the supporting members 3 are locked in place.

When all of the supporting members 3 have been properly placed upon the strip 95 1 and secured thereto, the device is ready for use. When used the device is placed upon the falsework upon which the concrete is to be poured and the bars 11 are placed upon the transverse part 7 of the supporting 100 members 3, and the arms 2 are then bent around the bar 11 in opposite directions as indicated in Fig. 1.

In the modification shown in Figs. 5 and 6, the supporting members 3 are secured in 105 place upon the strip 1 by causing a suitable punch to depress a part of the superimposed portions 7 of the supporting members and the strip 1 so as to form interfitting offset portions 12 and 13 respectively, as more 110 clearly indicated in Fig. 6.

As will be obvious, other modifications

may be made and those shown may be further modified or altered or have details omitted without departing from the spirit of this invention as defined by the following claims.

I claim:

1. In a device of the class described, the combination of a spacing member and a separately formed supporting member, each 10 of said members having a slot extending inwardly from one edge, the length of the slots in the two members being substantially equal to the width of one of said members, said members being assembled with the slot 15 in one member extending beyond the slot in the other and each slot embracing a part of the other member which is aligned with the slot therein, whereby said supporting member is positioned so as to support said 20 spacing member above the falsework.

2. In a device of the class described, the combination of a spacing member and a separately formed supporting member, each 25 of said members having a slot extending inwardly from one edge, the length of the slots in the two members being substantially equal to the width of one of said members, said members being assembled with the slot 30 in one member extending beyond the slot in the other and each slot embracing a part of the other member which is aligned with the slot therein, whereby said supporting member is positioned so as to support said 35 spacing member above the falsework, and interlocking parts on said members adapted to secure said members in said assembled relation.

3. In a device of the class described, the combination of a flat spacing strip having 40 notches extending inwardly from one of the edges thereof, and a plurality of supporting members for spacing said strip above the falsework, each of said members comprising a depending leg and a transversely disposed part, said leg having a slot extending 45 inwardly from the edge thereof below said transversely disposed part, said supporting members being assembled on said spacing strip by having said notches interfitting 50 with adjacent portions of the respective strip and supporting members.

4. In a device of the class described, the combination of a flat spacing strip having notches extending inwardly from one of the 55 edges thereof, a plurality of supporting members for spacing said strip above the falsework, each of said members comprising a depending leg and a transversely disposed part, said leg having a slot extending 60 inwardly from the edge thereof below said transversely disposed part, said supporting members being assembled on said spacing strip by having said notches interfitting 65 with adjacent portions of the respective strip and supporting members, and coacting

means on said strip and supporting members for securing said supporting members in position on said strip.

5. In a device of the class described, the combination of a flat spacing strip having a plurality of pairs of notches extending inwardly from one edge thereof at intervals along said strip, and a plurality of supporting members for supporting said strip above the falsework, each of said supporting members being substantially in the form of an inverted U so as to provide a pair of depending legs connected by a transversely disposed part, said members having notches formed in said legs directly below said transversely disposed part and being assembled on said spacing strip by having said notches in said members and strip interfit with adjacent portions respectively of the strip and supporting members. 85

6. In a device of the class described, the combination of a flat spacing strip having a plurality of pairs of notches extending inwardly from one edge thereof at intervals along said strip, a plurality of supporting members for supporting said strip above the falsework, each of said supporting members being substantially in the form of an inverted U so as to provide a pair of depending legs connected by a transversely disposed part, said members having notches formed in said legs directly below said transversely disposed part and being assembled on said spacing strip by having said notches in said members and strip interfit with adjacent portions respectively of the strip and supporting members, said strip also having recesses formed therein on the side opposite said notches and located between the respective pairs of notches, and lugs formed on the transversely disposed parts of said supporting members and bent into the respective recesses and around said strip so as to secure said supporting members to said spacing strip. 100 105 110

7. In a device of the class described, the combination of a flat spacing strip having notches extending inwardly from one of the edges thereof, a plurality of supporting members for spacing said strip above the falsework, each of said members comprising a depending leg and a transversely disposed part, said leg having a slot extending inwardly from the edge thereof below said transversely disposed part, said supporting members being assembled on said spacing strip by having said notches interfitting 115 with adjacent portions of the respective strip and supporting members, and bar clamping means in the form of arms struck out from said strip adjacent to each of said supporting members. 120 125

8. In a device of the class described, the combination of a flat spacing strip having a plurality of pairs of notches extending in- 130

wardly from one edge thereof at intervals along said strip, a plurality of supporting members for supporting said strip above the falsework, each of said supporting members 5 being substantially in the form of an inverted U so as to provide a pair of depending legs connected by a transversely disposed part, said members having notches formed in said legs directly below said transversely 10 disposed part and being assembled on said spacing strip by having said notches in said members and strip interfit with adjacent portions respectively of the strip and supporting members, and bar clamping means in the form of arms struck out from said strip at opposite edges thereof and on opposite sides of said supporting members. 15

Signed at Chicago this 13th day of October, 1919.

HENRY H. LAMPERT.
